INVENTOR

WALTER B. MAHL
Longbotham
ATTORNEY

UNITED STATES PATENT OFFICE.

WALTER B. MEHL, OF WALTHAM, MASSACHUSETTS, ASSIGNOR TO E. HOWARD WATCH COMPANY, OF RIVERSIDE, NEW JERSEY, A CORPORATION OF NEW JERSEY.

WATCH.

No. 922,013.

Specification of Letters Patent.

Patented May 18, 1909.

Application filed August 1, 1908. Serial No. 446,877.

To all whom it may concern:

Be it known that I, WALTER B. MEHL, a citizen of the United States, and a resident of Waltham, in the county of Middlesex and State of Massachusetts, have made and invented certain new and useful Improvements in Watches, of which the following is a specification.

My invention relates to an improvement in watches, and more particularly to the means employed for securing the movement in the case center or within a movement ring removably attached or pivoted to the center. It has heretofore been common to use screws either round or half headed, tapped at one end into the dial plate and passing through the train bridges or top plate, the head of the screw binding on the case center or movement ring at the train side thereof. As is well known to those skilled in the art, this method of securing the movement in place is objectionable for several reasons, particularly because any pressure exerted by the screw in order to retain the assembled parts in their proper relative positions, causes an undue strain or pressure to bear on the watch train, seriously affecting the accuracy or time keeping qualities thereof. As a matter of fact, I have found from experience that movements which perform very accurately before being fitted in the case, will often vary from ten to thirty seconds from accurate time in twenty-four hours, after being fitted in the case and the binding screws applied. Another objection to the use of binding screws employed as has heretofore been the custom, is the fact that the strain exerted by them tends to press inwardly that portion of the case center against which the heads of the screws impinge, thereby causing an opening or crevice between the parts, which permits of the entrance of dirt, dust, or other foreign matter to the movement.

Another and very serious objection urged against the customary manner of securing the movement in the case, is that in applying the screws to hold the movement within the center, a slight twist is given to the movement in the case center, thereby affecting the alignment of the winding stem or arbor.

The object of my invention is to overcome these difficulties, and with this and other

ends in view, the invention consists in certain novel features of construction and combinations of parts, as will be hereinafter fully described and pointed out in the claims.

In the accompanying drawings, Figure 1 is a plan view of a watch, parts of the bezel and dial being broken away for the sake of clearness. Fig. 2 is a sectional view taken on the line 2--2 of Fig. 1. Fig. 3 is a sectional view taken on the line 3--3 of Fig. 1. Fig. 4 is a detached view of one of the retaining lugs. Fig. 5 is a plan view of a watch showing my invention as applied to a watch case having a swinging movement ring. Fig. 6 is a sectional view taken on the line 6--6 of Fig. 5. Fig. 7 is a view of a part of the movement ring showing a retaining lug formed thereon, and Fig. 8 is a view of a part of the movement having one of the retaining lugs secured thereto, and adapted to be secured to the movement ring illustrated in Fig. 7.

Referring to the drawings, A represents a case center of ordinary construction, and has formed therein or secured thereto at such places where it is desired to apply the locking means, the lugs a, the snap or riser b formed on said center for the reception of the bezel B, being slightly cut away above said lugs a as clearly illustrated in Fig. 1 of the drawings.

To the dial plate C and on the dial side thereof, is secured the retaining lug D, preferably two in number, as illustrated in Figs. 1 and 5. These retaining lugs are shaped as shown, that is, comprise two disk-like plates d, d¹, the larger plate D having an opening d² therein for the passage of a binding screw, and centrally recessed for the reception of the head of the latter. The smaller plate d¹ is also provided with a hole or opening d³ for the passage of a binding screw through the same, as hereinafter described. The dial plate C is recessed on the dial side thereof to allow the larger plate d of the retaining lug D to set flush therein, a binding screw d⁴ being tapped into the dial plate C, adjustably holding said retaining lug D therein.

Through the opening d² in the plate d² of the retaining lug D, passes a retaining screw d⁵, the lower end of said screw being tapped into the lug a formed on or secured to the case center A, the screw d⁴ being hidden by the

dial E when the parts are properly assembled, and the screw d^5 hidden by the bezel B.

When assembling the parts, the retaining lugs D are secured to the dial plate C, and so 5 adjusted that the smaller plate d^3 thereof will register with the recesses or openings formed for their reception in the riser or snap b of the case center. The movement is then placed in the case center and the retaining 10 screws d^5 turned down into the lugs a, securely holding the movement in place in the case center.

It will be understood from the above that in 15 securing the movement in place, the watch is held in its most convenient position, that is, is held dial side up, whereby all danger of the movement dropping out of the case while being secured therein is avoided. Furthermore, by my improved means, all 20 the strain exerted by the binding screws d^4 , d^5 , falls on the case center A and dial plate C, and in no way or upon any part of the watch 25 train, as is the case when binding screws are employed in the customary manner. Furthermore, it will be seen that the retaining 30 lugs D are adjustable, thereby permitting a leeway for the correction of any inaccuracies in the location of the recesses formed in the case center to receive them. Again, by 35 reason of the accurate adjustment of the retaining lugs, no twisting of the movement occurs while applying it to the case center, the proper alinement of the winding arbor being thereby always preserved. Should, 40 however, it develop that after the movement has been secured in the case center, the alinement of the arbor is not perfect, no twist of the movement in the case is necessary, as by 45 loosening the screw or screws in the retaining lug, the latter may be sufficiently shifted or moved to permit of the correction of the 50 alinement. It will of course be understood that the binding screw d^4 may be countersunk in the retaining lug D, and tapped into the dial plate, as shown, or the dial plate 55 may be recessed or countersunk from the opposite side, and the screw d^4 tapped into the lug. Again, as illustrated in Figs. 5, 6, 60 7 and 8, my improved attaching means is 50 also adapted for use in connection with watch cases comprising in part, a movement 65 ring hinged, as illustrated at F, (Fig. 5), to the case center G. In this instance, the screw lugs f will be formed on or secured to the ring H instead of being formed on or 70 secured to the case center, as described in the former instance. The larger plate f^1 of the retaining lug, is recessed into the dial plate I, as in the former instance, and adjustably 75 held in place by the binding screw f^2 , a binding screw f^3 being passed down through the smaller plate f^4 of the retaining lug and 80 tapped into the screw lug f formed on the

ring H. In either instance the retaining lug and screws are hidden by the dial and bezel 85 when the parts are assembled, it being necessary only to raise or remove said bezel and to remove the binding screws from the smaller plate of the retaining lug to permit of the withdrawal of the movement from the case 90 center or movement ring.

The invention is exceedingly simple, the cost of manufacture being but little, if any more than that of the ordinary retaining means. Furthermore, the parts having 95 been once adjusted, the movement may be removed from and inserted in the case center with far more despatch and accuracy than has been the case heretofore, the perfect alinement of the winding stem or arbor being 100 always preserved. Again, all the strain of the binding screws having been withdrawn from the watch train, the time keeping qualities of the watch are greatly enhanced.

Having fully described my invention, what I claim as new and desire to secure by Letters Patent, is:

1. In a watch, a dial plate, a case center upon which said dial plate rests, and means 90 secured to the dial side of the dial plate, whereby to adjustably attach said dial plate to said case center, substantially as described.

2. In a watch, the combination with a 95 movement having a dial plate, of a case center provided with a flange upon which said dial plate rests, means adjustably secured to the dial side of the dial plate and to said case center for retaining said movement in 100 position on the flange of the latter, substantially as described.

3. In a watch, the combination with a dial plate, of a retaining lug adjustably secured to the dial side of said plate, and a case center 105 provided with a supporting flange on which said dial plate rests, and means contained within said case center to which said retaining lug is movably secured for holding said movement in position on the flange of 110 said case center, substantially as described.

4. In a watch, the combination with a dial plate formed with a recess in the dial side thereof, of a retaining lug partially and movably fitting in said recess, a case center 115 provided with a supporting flange on which said dial plate rests, and means contained within said center to which said lug is removably secured for retaining the movement in position on said flange, substantially as described.

5. In a watch, the combination with a 120 movement, consisting in part of a dial plate, having a recess formed on the dial side thereof, a watch case comprising in part a case center provided with screw lugs, a retaining lug fitting in said recess in said dial plate and 125

screws passing through said retaining lug into said dial plate and into the lugs in said case center, whereby said movement is removably and adjustably held in the case center on the dial side thereof, substantially as described.

Signed at Waltham, in the county of Mid-

Essex, and State of Massachusetts, this 27th day of July A. D. 1908.

WALTER B. MEHL.
